(57) **CLAIM**

The ornamental design for an ultrasonic/electromagnetic pest repeller, as shown and described.

DESCRIPTION

FIG. 1 is a front perspective view of the ultrasonic/electromagnetic pest repeller;

FIG. 2 is front elevation view thereof;

FIG. 3 is a right elevation view, with the left elevation view being a mirror image thereof;

FIG. 4 is a rear elevation view thereof; and,

FIG. 5 is a top plan view, with the bottom plan view being a mirror image thereof.

The broken lines depict environmental structure and are for illustrative purposes only and form no part of the claimed design.
